DESIGN FOR A BURIAL VAULT

Ramon S. Cram, Upper Sandusky, Ohio, assignor to The Wyandot Vault Company, Upper Sandusky, Ohio, a corporation of Ohio

Application September 5, 1933. Serial No. 49,198

Term of patent 7 years

To all whom it may concern:

Be it known that I, RAMON S. CRAM, a citizen of the United States, residing at Upper Sandusky, in the county of Wyandot and State of Ohio, have invented a new, original, and ornamental Design for Burial Vault, of which the following is a specification, reference being had to the accompanying drawing, forming part hereof, wherein the figure is a perspective view of such burial vault.

I claim:

The ornamental design for a burial vault substantially as shown.

RAMON S. CRAM.
